UNITED STATES PATENT OFFICE

ABE O. SAMUELS, OF ROCHESTER, NEW YORK, ASSIGNOR TO SAMSON-UNITED CORPORATION, OF ROCHESTER, NEW YORK, A CORPORATION OF DELAWARE

DESIGN FOR A SADIRON COVER

Application filed February 5, 1930. Serial No. 34,417. Term of patent 14 years.

To all whom it may concern:

Be it known that I, ABE O. SAMUELS, a citizen of the United States of America, residing at Rochester, in the county of Monroe and State of New York, have invented a new, original, and ornamental Design for Sadiron Cover, of which the following is a specification, reference being had to the accompanying drawing, forming a part thereof.

Figure 1 is a plan view of a sadiron cover embodying my design.

Figure 2 is a side elevation;

Figure 3 is a rear end elevation, and

Figure 4 is a front end elevation.

I claim:

The ornamental design for sadiron cover, as shown.

ABE O. SAMUELS.
